UNITED STATES PATENT OFFICE.

MARGARET ANNA ELIZABETH LUHRS, OF HOBOKEN, NEW JERSEY.

FOLDING ATTACHMENT FOR SEWING-MACHINES.

No. 815,026.

Specification of Letters Patent.

Patented March 13, 1906.

Application filed April 29, 1905. Serial No. 257,987.

To all whom it may concern:

Be it known that I, MARGARET ANNA ELIZABETH LUHRS, a citizen of the United States, and a resident of Hoboken, in the county of Hudson and State of New Jersey, have invented certain new and useful Improvements in Folding Attachments for Sewing-Machines for Making Bias Folds for Application to Ladies' Dresses, of which the following is a specification.

My invention relates to a sewing-machine attachment for the making of bias folds, ruffles, ruches, and corded or uncorded ruffles.

My invention is illustrated in the accompanying drawings, in which—

Figure 1 is a perspective view of my folder attached to a sewing-machine. Fig. 2 is a plan view of my improvement. Fig. 3 is a cross-section of a part thereof on line 3 of Fig. 2.

The part marked 1 on the drawings represents the bed-plate of the sewing-machine. The part marked A is the folder, consisting of a strip of sheet metal or other material of the proper size bent to form a flattened oval orifice a' with overlapping edges a^2 and a^3 , leaving the longitudinal slot a^4 . The flattened orifice is of a width corresponding with the width of the material after it is folded.

B is the connecting-plate to which the folder is attached, and this connecting-plate is secured to the bed of the machine by a thumb-screw C, passing through the slide D of the connecting-plate into an opening (not shown) in the bed of the machine. The slide D is provided with an elongated opening d , which enables the folder to be adjusted transverse of the machine. The connecting-plate B is cut away at $b' b^2 b^3$, leaving the longitudinal strips $b^4 b^5$, to which the slide D is attached by the overturned ends $d' d^2$ and which permits the connecting-plate B and of course the folder carried thereby to be adjusted transverse of the machine.

E is the head of the machine and carries the usual presser-foot F, needle-bar G, and needle g.

When the attachment is secured to the machine, it may be adjusted by loosening the thumb-screw C, when it can be moved transversely of the machine, and the plate B may

be moved longitudinally of the machine by moving it in either direction when the strips b^4 and b^5 are free to move through the overturned ends $d' d^2$ of the slide D. When the attachment is properly adjusted, it is clamped in position by the screw C. The material is placed in the folder by turning over the edge of the cloth and folding the cloth and passing the edge of the cloth through the slot a^4 , and the cloth is moved backward and forward until it is flattened down and fills up the orifice a' . It is then pushed under the presser-foot and the machine is operated. As the needle sews the edge of the material the said material is fed to the needle and will be properly and accurately folded, and this is done without any marking or any special skill.

What I claim, and desire to secure by Letters Patent, is—

1. A folding attachment for sewing-machines, consisting of a plate folded to form an open-edge flattened tube, one of the edges of said plate being straight and the other edge overlapping the straight edge leaving a slot between the two edges through which the material to be operated on may be inserted, a plate extending from said tube, said plate being provided with strips, a slide connected to said strips and adapted to move longitudinally thereon, said slide having an opening therein in a direction transverse to the strips, and adapted to receive a screw by which the attachment may be secured to the bed of a machine.

2. A folding attachment for sewing-machines consisting of a flattened tube one edge of which overlaps the other but with a longitudinal opening between through which the material is to be inserted, a plate secured to the tube, said plate having parallel strips, a slide secured to move longitudinally on said strips, said slide having an opening therein adapted to receive a set-screw by which the attachment is secured to the bed of the machine.

3. A folding attachment for sewing-machines consisting of a flattened tube one edge of which overlaps the other, there being left a longitudinal slot between the edges of the tube through which the material is to be inserted, a plate secured to the tube, said plate

having parallel strips, a slide turned over the edges of the strips by which it is secured to the strip and adapted to be moved longitudinally thereof, said slide being provided with a 5 longitudinal slot and a set-screw passing through the slot and into the bed of the machine.

In witness whereof I have hereunto set my hand, in the city, county, and State of New York, this 28th day of April, 1905.

MARGARET ANNA ELIZABETH LUHRS.

In presence of—

JOHN J. RANAGAN

T. R. RICHARDS.
